AUTOMATIC DEVICE FOR TAPPET VALVE
ADJUSTMENTSHerbert H. Engemann and Henry H. Burdick,
Pontiac, Mich.

Application February 3, 1932, Serial No. 590,578

10 Claims. (Cl. 123—90)

The present invention relates broadly to hydrocarbon engines and more especially to an automatic adjustment device for the valves thereof.

In the operation of hydrocarbon engines, it is usual to provide a poppet valve and cam operated tappet mechanism for opening the valve, the valve being maintained against the valve seat by spring pressure. One of the problems of hydrocarbon engine operation is the maintenance of the adjustment of the relation between the tappet and the valve stem in order that the valve may be opened and closed at the proper time. It is very desirable to maintain a slight clearance between the tappet and the end of the valve stem in order that the entire spring pressure on the valve stem may be effective to seat the valve head against the valve seat. The valve parts being made of metal change in length when the parts become heated. Therefore, adjustments for a cold motor are not proper for the motor when it is heated and vice versa.

The present invention overcomes the difficulties above outlined by providing mechanism to maintain a constant predetermined clearance in the line of valve operating mechanism and preferably between the tappet and the valve stem regardless of thermal conditions or wear. In accordance with the present invention, compensating adjustments are made for each cycle of valve operation. These adjustments are brought about by mechanism operated by the same power which reciprocates the valve stem, and the adjustments are maintained while the valve is being opened but are released when the valve is closed.

While the present invention in the preferred form is illustrated as associated with an L-head type internal combustion engine, it is to be understood that the principles of the present invention are applicable to any type of hydrocarbon engine using tappet valve mechanism. It is also to be understood that while the preferred form of the invention has been illustrated to conform to the patent laws, that the invention may be embodied in different devices and mechanisms from those specifically illustrated herewith so that the disclosure herewith is to be understood as illustrative and not in the limiting sense.

Fig. 1 is an elevational view of a valve adjusting mechanism according to the present invention.

Fig. 2 is a side view of the adjustment mechanism taken on line 2—2, Fig. 1.

Fig. 3 is a detail view of a part of the mechanism taken on line 3—3, Fig. 1.

Fig. 4 illustrates the position of the parts with the valve open to full position.

Fig. 5 illustrates the valve closed and the tappet having just released the pressure on the adjusting mechanism sufficient for the parts to move to non-adjusted position just before the parts are moved to adjusting position shown in Fig. 6.

Fig. 6 illustrates the parts with the adjustment completed and a valve stem being ready to be raised.

Referring to the drawings and more especially to Fig. 1, a valve 1 is mounted in the usual way for reciprocal movement in an engine head 2 and the stem of the valve 4 carries on its lower end a spring collar 5 held in position by a cross pin 6 extending through the valve stem 4. A strong coil spring 7 extends between the spring collar 5 and an abutment 8 which may comprise a part of the engine head.

A cam 9 operates a tappet which may comprise a pair of screw threaded members 10 and 11 adapted to be held in position by a lock nut 12 whereby major adjustments may be made during the assembly of the engine.

An important feature of the present invention comprises a constant clearance device which preferably comprises a cup 14 adapted to receive the lower end of the valve stem 4. This cup 14 carries a spacer plate 15 through which pass securing members that in the preferred form are illustrated as rivets 16. A plate spring 17 is provided with openings through which the rivets 16 pass and is bent in the form of a bow in such manner as to tend to separate the spacer plate 15 from the bottom of the cup 14. The amount of separation is determined by the distance the spacer plate 15 may move on the rivets 16. This operation of the spring 17 provides a clearance 18 comprising the distance between the cup 14 and the spacer plate 15 minus the thickness of the plate spring 17. This clearance is therefore a constant clearance which is maintained at all times until the plate spring 17 is flattened by compressive forces. The coil spring 7 is of a sufficient initial set so that when the tappet is raised by the cam 9, the plate spring 17 will be entirely flattened before the spring 7 yields to compression to lift the valve 1 from its seat.

One purpose of the device of the present invention is to maintain this constant clearance in the operating line between the operating cam and the valve head. This constant clearance is established by the mechanism previously de-

scribed comprising the cup 14, the spacer plate 15 and the plate spring 17 and to maintain it, it becomes necessary to compensate for wear and for thermal expansion and contraction of the parts. The preferred mechanism for overcoming play or slack comprises preferably a wedge mechanism operative to compensate for wear and expansion. Preferably, this wedge mechanism operates once during each cycle of valve operation so that the adjustment is made just prior to the valve operation whereby the parts are always set in proper adjustment when the valve operation cycle begins. Referring to Figs. 1, 2, and 3, an extension 19 from the head of the motor may comprise a support for the compensating mechanism. The compensating mechanism is carried on a frame plate 20 which is suitably secured to the extension 19 by bolts or screws 21 suitably locked in place. A pair of arms 22, 24 are provided with slots 25, 26 through which extend pivot studs 27, 28 that are riveted into the frame plate 20. The arms 22, 24 are therefore both pivotally and slidably mounted on the pivot studs. These arms 22 and 24 are hinged at their lower ends to compensating wedges 29 and 30, which wedges are slidable between the member 11 of the tappet and the spacer plate 15 on the constant clearance cup 14 so that when the compensating wedges are forced inward, all extraneous linear space has been compensated for or taken up. The arms 22, 24 are provided with lugs 31, 32 which carry flat springs 34, 35. The frame plate 20 is also provided with lugs 36 and 37 on which are mounted flat readjusting springs 38, 39 that bear against the lugs 31, 32 on the levers 22, 24. The middle portion of the frame plate 20 is provided with a vertical slot 40 parallel to the axis of movement of the valve stem 4. A slide plate 41 is mounted over this slot 40 and carries an operating pin 42 which extends into the path of movement of the spring collar 5 on the stem 4 of the valve. The upper end of the slide plate 41 is guided by a stud rivet 44. A pair of contact links 45, 46 are pivotally mounted at their inner ends on the slide plate 41 and are mounted to slide on studs 47, 48 carried by the frame plate 20. A return spring 49 (Fig. 3) is mounted upon an adjustment segment 50 provided with a segmental slot 51 and a locking screw 52 screw threaded into the frame plate 20 so that the outer end of the return spring 49 may be adjusted relative to the position of initial contact with the operating pin 42 carried by the slide plate 41.

The operation of the device may be followed more easily by reference to Figs. 4, 5 and 6. Fig. 4 illustrates the cam 9 at its highest lift point with the valve 1 open. Under these conditions, the wedges 29 and 30 are tightly clamped between the upper end 11 of the tappet and the spacer 15 carried by the cup 14, due to the strong resistance of the heavy coil spring 7. The operating pin 42 has contacted with the spring collar 5 and has been carried upwardly, thereby moving the slide plate 41 upwardly and swinging the contact links 45, 46 outwardly to place the flat hairpin springs 34, 35 under tension, which would tend to swing the arms 22, 24 outwardly and thus tend to carry the compensating wedges 29, 30 outwardly. The tension on the springs 34, 35 is not sufficiently great, however, to overcome the friction holding the wedges in place due to the pressure of the cam 9 acting against the force of the heavy coil spring 7. Under this condition, it will be observed that

the plate spring 17 is flattened and the constant clearance space 18 has been taken up before the valve 1 starts to open.

As soon as the cam 9 has rotated to lower the valve stem to its lowermost position whereby the force of the spring 7 is expended against the spring collar 5 without further movement of the valve stem, the wedges 29 and 30 are no longer tightly clamped, and, therefore, the tensions on the springs 34, 35 operate to swing outwardly the arms 22, 24 and thereby withdraw the wedges 29, 30 as is illustrated in Fig. 5. In the mean time, when the operating pin 42 was lifted by the valve spring collar 5, the outer end of this pin tensioned the return spring 49 (Fig. 3). The return spring 49, however, is not of sufficient strength to move the slide plate 41 until after tension on the hairpin springs 34, 35 is relieved. As soon as this tension is relieved by the withdrawal of the compensating wedges as illustrated in Fig. 5, the return spring 49 operates to snap the slide plate 41 downwardly to its lowest position as illustrated in Fig. 6. When this happens, the return flat readjusting springs 38, 39 carried on the lugs 36, 37 on the frame plate 20, and which were stressed when the arms 22, 24 swung outwardly as illustrated in Fig. 5, now operate to swing the arms 22, 24 inwardly since these springs 38, 39 are now the only forces at present acting on the arms 22, 24. Consequently, the compensating wedges 29 and 30 are forced into place between the member 11 of the tappet and the spacer plate 15 carried by the cup 14. The force exerted by the springs 38, 39 is not a heavy force, and, therefore, the wedges 29 and 30 are not moved together with a force sufficiently great to flex the plate spring 17 which is acting at this time to maintain the constant clearance 18. It will be noted the wedges 29, 30 snap out quickly when the cam pressure on the tappet is released, and that these wedges are immediately snapped back into compensating position by the operation of the return spring 49 which moves the links 45, 46 so as to release the effective energy stored in the flat readjusting springs 38, 39 to swing the arms 22, 24 inward.

From the foregoing, it will appear that the present invention provides first, a constant clearance space in the operating line between the operating cam and the valve, which space is taken up when the cam functions to operate the valve; second, the present invention takes up and eliminates all other extraneous or undesirable slack in the operating line between the operating cam and the valve head so that all that is left is the predetermined constant clearance. In this way, a constant operating condition is provided for the valve regardless of wear or thermal expansion and contraction.

What we claim is:

1. In a valve operating mechanism for hydro-carbon engines, the combination of power means, a valve, connections between said power means and said valve whereby said valve is operated, said connections comprising a plate, a stop to limit the movement of said plate and a spring to move said plate against said stop to establish a predetermined clearance when the valve is closed, and means operative during each valve operating cycle to adjust said connections to take up all lost motion therein with the exception of the predetermined clearance.

2. In a valve operating mechanism for hydro-carbon engines, the combination of a valve, a cam, connections for transmitting motion from

- said cam to said valve, means to establish a predetermined clearance in said connections when said valve is closed, a pair of wedges, spring means energized by the cam to withdraw said wedges, and means to insert said wedges to take up lost motion in said connections prior to the action of said cam on said connections to open said valve.
3. In a valve operating mechanism for hydrocarbon engines, the combination of power means, a valve, connections between said power means and said valve whereby said valve is operated, said connections comprising means to establish a predetermined clearance when the valve is closed, wedge means to take up all lost motion in said connections with the exception of the predetermined clearance, spring means to adjust said wedge means to inoperative and then to operative position for each operation of said valve.
4. A valve operating mechanism for hydrocarbon engines comprising a valve, a spring normally tending to hold said valve closed, thrust means to oppose the action of said spring and open said valve, a cam to operate said thrust means, said thrust means comprising a pair of wedge members movable transversely of the line of thrust, a pair of springs energized by the force opening said valve to withdraw said wedges from operative position when the valve is closed, and means to reinstate said wedges into operative position to take up any lost motion in said thrust means before said valve is opened.
5. Valve operating mechanism for hydrocarbon engines comprising a valve having a valve stem, a valve spring for seating said valve against a valve seat, a tappet rod for opening said valve, spring means to maintain a predetermined clearance between said valve stem and said tappet rod when said valve is closed, wedge means movable at substantially right angles to the line of movement of said tappet rod, spring means operated by the force opening said valve to snap said wedge means to inoperative position when the valve is seated, and additional spring means to snap said wedge means to operative position before the valve is reopened.
6. In a valve operating mechanism for hydrocarbon engines, the combination of a valve, a cam to operate said valve, mechanism for transmitting motion from said cam to said valve comprising means to maintain a predetermined clearance in said mechanism when the valve is seated, and means acting automatically at predetermined periods in the cycle of valve operations to adjust the mechanism between the valve and the cam to introduce excessive lost motion and then to take up lost motion therein to maintain said clearance as the sole clearance between said valve and said cam.
7. In a valve operating mechanism for hydrocarbon engines, the combination of a valve, a cam for operating said valve, connections for transmitting motion from said cam to said valve, means for automatically adjusting said connections prior to each valve opening movement to introduce excessive lost motion in said connections and then to take up lost motion in said connections prior to the action of the same cam on said connections to open said valve, and means to establish a predetermined clearance in said connections when said valve is closed and when said means for adjusting said connections have operated to make said valve adjustment.
8. Valve operating mechanism for hydrocarbon engines comprising in combination a valve, a spring tending to hold said valve closed, thrust means to open said valve, a valve stem against which said thrust means is effective, wedge means carried by said thrust means and operative to eliminate lost motion of said thrust means, means to render said wedge means inoperative and then operative, and devices for maintaining predetermined clearance between said valve stem and said thrust means when said valve is closed and after said wedge means have become operative to take up said lost motion.
9. Valve operating mechanism for hydrocarbon engines comprising a valve having a valve stem, a valve spring for seating a valve against a valve seat, a tappet rod for opening said valve, wedge means movable at substantially right angles to the line of movement of said tappet rod, devices operated by the force opening said valve to withdraw said wedge means when the valve is seated and to reinstate said wedge means before the valve is opened, and means to establish a predetermined clearance between said valve stem and said tappet rod when said wedge means are seated.
10. Valve operating mechanism for hydrocarbon engines comprising in combination a valve, a spring tending to hold said valve closed, a tappet to open said valve, a valve stem against which said tappet is effective, a cam to operate said tappet, wedge means between said tappet and said valve and operative to eliminate lost motion, means to completely readjust said wedge means for each cycle of operation of said valve, and means to establish a predetermined clearance between said valve stem and said tappet after said valve is closed.
